The ornamental design of a golf swing training guide, as shown and described.

DESCRIPTION

FIG. 1 is a front elevational view of a golf swing training guide in accordance with my design and showed in a collapsed condition of the golf swing training guide as intended for storage;

FIG. 2 is a top plan view of my golf swing training guide in the condition shown in FIG. 1;

FIG. 3 is a side elevational view as viewed from the left in FIG. 2;

FIG. 4 is a side elevational view as viewed from the right in FIG. 1;

FIG. 5 is a rear elevational view of my design in the FIG. 1 condition;

FIG. 6 is a bottom plan view of my design in the FIG. 1 condition;

FIG. 7 is a front elevational view of my design in its expanded and ready-to-use condition;

FIG. 8 is a top plan view of my design in the FIG. 8 condition;

FIG. 9 is a side elevational view as viewed from the left in FIG. 7;

FIG. 10 is a side elevational view as viewed from the right in FIG. 7;

FIG. 11 is a rear elevational view of my design in the FIG. 7 condition;

FIG. 12 is a bottom plan view of my design in the FIG. 7 condition;

FIG. 13 is a top plan view of my design in the collapsed condition of FIG. 1, but showing a preferred array of indicia imprinted thereon; and,

FIG. 14 is a top plan view of my design in the FIG. 7 condition but showing my preferred array of indicia thereon.
